2 SHEETS--SHEET 2.

UNITED STATES PATENT OFFICE.

PAUL BRILL, OF JACKSON, MICHIGAN.

PAPER-HANGING MACHINE.

Application filed January 31, 1922. Serial No. 532,956.

To all whom it may concern:

Be it known that I, PAUL BRILL, a citizen of the United States, residing at Jackson, in the county of Jackson, State of Michigan, have invented a new and useful Paper-Hanging Machine; and I do hereby declare the following to be a full, clear, and exact description of the invention, such as will enable others skilled in the art to which it appertains to make and use the same.

The invention relates to paper hanging machines, and has for its object to provide a device of this character in which a roll of paper may be placed and the free end passed upwardly under an elongated brush for applying the paper to a wall on which an adhesive has been placed when the machine is moved downwardly by the operator.

A further object is to provide means whereby different lengths of rolls of paper may be received and held within the machine. Also to provide means whereby the width of the brush may be varied according to the width of the paper.

A further object is to provide a paper hanging machine having a handle member, outwardly adjustable frames carried by said handle member, said frame being provided with means for supporting a roll of paper, and also with overlapped elongated brushes slidably connected, the length of the brush as a whole being automatically extended to comply with the width of the roll of paper being held in the machine. Also to provide the outer ends of the adjustable frame with supporting rollers adapted to engage the wall and roll over the same during the downward movement of the invention.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

50 In the drawings:—

Figure 1 is a side elevation of the paper hanging machine.

Figure 2 is a rear elevation of the paper hanging machine.

Figure 3 is a vertical sectional view 55 through the machine taken on line 3—3 of Figure 2.

Figure 4 is a detail perspective view of one end of the pivoted brush.

Referring to the drawings the numeral 1 60 designates a handle member, which handle member has secured thereto by means of a rivet 2 a guide yoke 3. Extending through the guide yoke 3, are the arms 4 and 5 of the inwardly and outwardly movable frames 65 6 and 7. The arms 4 and 5 have secured thereto yokes 8, in which the adjacent arms are slideable and guided when the frames 6 and 7 are adjusted inwardly or outwardly according to the width of the roll of paper 9. 70 Secured to the upper end 10 of the handle member 1 is a second yoke 11, in which yoke the arms 4^a and 5^a of the frames 6 and 7 are slidably mounted. Said arms are held in registration during the slidable engagement 75 thereof by means of yokes 12 in which the adjacent arms are mounted. It will be seen that the frames 6 and 7 may be adjusted inwardly and outwardly and held in adjusted positions by means of set screws 13. 80

The outer ends of the arms 4 and 4^a are secured to a segmentally shaped bracket 14, and extending outwardly from said bracket 14 is an arm 15, which terminates in a forwardly extending arm 16. The forwardly extending arm 16 has secured thereto by means of rivets 17, a plate 18. It will be seen that as the frame 6 is adjusted inwardly or outwardly the plate 18 will move therewith, thereby varying the distance between the plate 18 and the plate 19 carried by the frame 7 for receiving therebetween on the shaft 20 various lengths of rolls of paper according to the standard sizes. The roll supporting shaft 20 extends through 95 apertures 21 in the plates 18 and 19, and through apertures of spring plates 22, which plates flex slightly and hold the shaft against movement after the plates have been adjusted the proper distance apart and a 100 roll of paper of the desired width placed therein. If so desired cotter pins 23 may be provided in the ends of the shaft 20 for preventing the shaft from coming entirely

out of the apertures 21. Pivots mounted on the arm 16 of the plate 18 and on the arm 24 of the plate 19 are guide wheels 25, which wheels during a paper hanging operation engage the wall 25^a and guide the device as the operator moves the same downwardly. The free end of the paper from the roll 9 extends forwardly and upwardly over a guide rod 26, and thence to a point beneath the elongated brush 27, which brush during the downward movement of the machine presses the wall paper into engagement with the wall 25^a which has been previously coated with an adhesive, thereby causing the paper to adhere to the wall. The rod 26 has its ends extending through apertures 28 in the plates 18 and 19, and through apertures of spring plates 29, which plates closely bind on the rod 26, and prevent longitudinal movement of the rod under normal conditions. The brush 27 is formed in two sections 30 and 31, which sections overlap each other and are slidably connected together by means of the H-shaped members 32 which extend through registering slots 33, and through the brush bars 34 and 35. The brush bar 34 has secured to its outer end by means of rivets 36 a bracket 37, which bracket is in turn provided with a pintle 38 pivotally mounted in a bearing 39 of the plate 19 and moved with said plate 19 as it moves inwardly and outwardly. The brush bar 35 has secured thereto a plate 40, which plate is provided with a pintle 41, pivotally mounted in the upper end of the segmentally shaped bracket 14. It will be seen that the brush bars 34 and 35, when the frames 6 and 7 are adjusted inwardly and outwardly will move with said frames and be guided in their movements by means of the H-shaped members 32 extending through the registering slots 33 therein. By simultaneously varying the length of the brush sections 30 and 31 as the frames 6 and 7 are adjusted for various widths of wall paper, it will be seen that the device will be wide enough to engage the outer face of the wall paper for its entire width when the same is applied to a wall. The bars 33 and 34 of the brush sections 30 and 31 are slidably mounted between the arms 42 of a plate 43, which plate is vertically disposed and has its lower curved edge 44 in slidable engagement transversely and longitudinally on the arm 5^a of the frame 7. The plate 43 when moved downwardly at its rear end 45, moves the brush 27 on its pivotal points and changes the inclinations of the brush 27 as desired. After the rear end 45 of the plate 43 has been moved to the desired position, the thumb nut 46 is tightened, thereby binding the plate 43 by means of the bolt 47 which passes through the upper end of the handle

member 1 and the segmentally shaped slot 65 48, and consequently holds the brush 27 against pivotal action.

From the above it will be seen that a paper hanging machine is provided which may be easily and quickly adjusted for receiving rolls of wall paper of varying widths, and that the brush 27 will be simultaneously extended or shortened in accordance to the adjustment of the device for receiving the roll of wall paper. 75

The invention having been set forth what is claimed as new and useful is:—

1. A wall paper hanging machine, said machine comprising a handle member, a frame carried by said handle member, means 80 for detachably supporting a roll of wall paper in said frame, means whereby said frame may be extended for receiving and holding rolls of wall paper of different lengths, a brush carried by said frame and 85 disposed above the roll of wall paper and means whereby when said frame is extended said brush will be simultaneously lengthened.

2. The combination with a wall paper machine comprising an extensible frame for the reception of rolls of wall paper of different lengths, of a paper engaging brush carried by said frame, said brush being so constructed that when the frame is extended 95 the length of the brush will be simultaneously changed.

3. The combination with an extensible wall paper roll receiving frame of a wall paper hanging machine, of an extensible 100 brush carried by said frame and means whereby upon an extension of the frame said brush will be simultaneously extended.

4. The combination with a wall paper hanging machine comprising an extensible 105 frame, said frame being formed in two sections slidably engaging each other, of a paper engaging brush carried by said frame, said brush being formed from two sections, the outer ends of the sections of the brush 110 being connected to the sections of the extensible frame, the inner ends of said brush being overlapped and slidably connected to each other, said brush being simultaneously extended or shortened upon movement of the frame sections. 115

5. A paper hanging machine comprising a handle member, a frame carried by said handle member, said frame being formed from two sections having inwardly 120 extending arms, the arms of the frame section overlapping each other and slidably connected, said slidably connected arms being slidably mounted in bearings of the handle, means for preventing slidable movement 125 of the arms in the bearings of the handle, means for supporting a roll of wall paper in the frame, a brush for engaging paper

as it is applied to a wall, said brush comprising overlapped brush sections slidably connected together, the outer ends of said brush sections being supported by the frame
5 sections and adjustable inwardly and outwardly therewith, and means for varying the angle of the brush.

In testimony whereof I have signed my name to this specification in the presence of two subscribing witnesses.

PAUL BRILL.
